DRILL PIPE PROTECTOR

Edward Craig and William O. Cooper, Brea, Calif.

Application September 19, 1930
Serial No. 483,006

7 Claims. (Cl. 308—4)

This invention relates to a device for use in connection with well drilling apparatus, and relates more particularly to a protective guide and bearing device for rotary drill pipe of the same general character as that fully described and claimed in our copending application entitled Drill pipe protector, Serial No. 441,842, filed April 5, 1930.

It is a general object of this invention to provide a protector of the character mentioned that can be quickly arranged and set in an operating position on the exterior of a well drilling string, or the like.

It is another object of this invention to provide a protector of the character mentioned that materially adds to the trueness of the well bore and assists in keeping the operating string in vertical alignment.

Another object of the invention is to provide a protector of the character mentioned that is effective in taking wear between the operating string and casing and which minimizes friction between the operating string and casing.

It is another object of the invention to provide a protector for well drilling parts which has a plurality of bearing blocks held in a sectional cage or carrier.

It is a further object of the invention to provide a protector for use in connection with a well drilling string that may be used to advantage to operate within casing set in the well or to operate in the open well bore below the lower end of the set casing, and that may be arranged or assembled for operation of drill pipe, drill pipe couplings, tool joints, drill collars, or any other part of a drilling string.

Other objects and features of our invention will be best and more fully understood from the following detailed description of typical preferred forms and applications of the invention, throughout which description reference is had to the accompanying drawings, in which:

Fig. 1 is a horizontal detailed sectional view of a well bore showing a drilling string within the casing and showing the device provided by this invention in plan elevation assembled to the drilling string. Fig. 2 is an enlarged vertical detailed sectional view taken as indicated by line 2—2 on Fig. 1 showing the means for positioning the protector on the drilling string. Fig. 3 is an enlarged vertical or longitudinal detailed sectional view taken as indicated by line 3—3 on Fig. 1. Fig. 4 is an enlarged view taken as indicated by line 4—4 on Fig. 1. Fig. 5 is a reduced side elevation of the protector illustrating the bearing parts and body construction. Fig. 6 is a transverse detailed sectional view taken as indicated by line 6—6 on Fig. 5 showing the corrugated formation of the bumpers. Fig. 7 is a horizontal detailed sectional view of another form of the invention. Fig. 8 is a vertical longitudinal sectional view of the protector taken as indicated by line 8—8 on Fig. 7, and Fig. 9 is an enlarged transverse detailed sectional view of a portion of the individual bumpers illustrating part of the protector in section.

The protector of this invention may be used to advantage in connection with many well operations and may be employed for many different uses other than that about to be described. For purpose of example, throughout the following description, the protector has been described as applied to a drilling string operating within a casing. It is to be understood, however, that this particular description is used merely for illustration and is not to be construed as a limitation, but is to be taken in the light of the appended claims.

The form of the invention illustrated in Figs. 1 to 6, inclusive, of the drawings includes, generally, a cage 10 adapted to be arranged on the object P, which may be a drill pipe, or the like, locking means 11 adapted to position or lock the cage 10 on the pipe P, and bumpers or wearing parts 12 arranged on the cage for protecting the drill pipe P, casing C, or well bore W.

The cage 10 is provided to carry the bearing parts 12 and is in the form of a substantially annular assembly. The cage includes two spaced rings, an upper ring 13 and a lower ring 14, spaced apart vertically or longitudinally on the drill pipe P, or the like. The rings 13 and 14 are connected by circumferentially spaced ribs 15. The inner sides of the rings have alternating depressions 16 and projections 17. The projections 17 extend longitudinally of the drill pipe P and are curved as at 17^a to seat against the surface of the drill pipe. The rings are arranged to be set on a drilling string, drill collar, or other well tool without being slid over its end. In order to accomplish this the cage is split longitudinally at 100 diametrically opposite points between the ribs 15 forming two sections A and B. Each section may be integral or built up of separate pieces. As is shown, the corresponding portions of the rings 13 and 14 are spaced apart vertically by the ribs 105 15 and are designated as sections A and B. In practice the sections A and B are made separate and hinged or pivoted together where they join at one side of the pipe. The sections are provided with overlapping parts. A pivot pin 18 is pro- 110

vided to engage the two sections through the overlapping parts. The upper and outer edge or corner of the ring 13 is beveled as is the lower and outer edge of the lower ring 14. The rings are thus beveled so that the device will offer little resistance to the fluid in the hole and to allow the device to move freely longitudinally in the well.

The means 11 provided for locking the cage 10 on the drill pipe is such that the device may be securely locked on the pipe so that it is positively held against longitudinal and circumferential movement. The means 11 operates to hold the free ends of the sections A and B together and to grip the object on which the cage is set. The means for locking the free ends of the sections A and B is in the form of a wedge means operable to draw the sections together and bring their various parts into tight engagement with the object P. The free ends of the sections B and A are provided with overlapping parts 19 and 20, respectively, which engage one another when the sections are in operative position around the drill pipe. The parts 19 of the section B seat in recesses 21 in the section A. The parts 20 of the section A seat in recesses 22 in the section B. Openings 24 are provided in the parts 19 and 20 which are brought into register when the device is set on the pipe. A longitudinally tapered pin 25 is driven through the openings 24 of the parts to clamp or set the two sections tightly onto the object P. The openings 24 are proportioned and related so that when the pin 25 is driven through them the sections are drawn onto the object. The large end of the pin 25 may be provided with a head 26 which may seat against the upper face of the section B. The small or lower end of the pin may be provided with a cotter pin or key 29 to prevent displacement of the pin.

Grips or gripping parts 30 are provided on the sections A and B to prevent longitudinal and circumferential movement of the device on the pipe P. The gripping parts 30 are in the form of pointed or sharpened projections extending inwardly from the inner sides of the rings 13 and 14. The gripping parts 30 are adapted to bite and grip into the object P to positively prevent the cage from shifting on the drilling string. In accordance with the preferred form of the invention the gripping parts 30 are formed of hard metal and are set in circumferentially spaced sockets in the rings 13 and 14. The parts 30 may be press fitted, welded or secured in the sockets in any suitable manner. The sharpened ends of the parts 30 project radially from the inner faces of the rings to engage the pipe P. When the wedge pin 25 is driven in the openings 24, the gripping parts are forced into biting engagement with the drill pipe P. If desirable, notches, recesses, or sockets may be formed in the pipe prior to the cage being arranged about it to receive the pointed ends of the parts 30.

The bearing parts 12 are provided on the cage 10 to protect the drill pipe to guide it in a well bore, and to protect the drill pipe and the well casing. In accordance with this form of the invention bearing parts are stationarily mounted on the cage between the rings 13 and 14. The parts 12 may be formed of rubber or a suitable rubber composition and are preferably integral members. There is a bearing and protective part 12 mounted on each section A and B. The bearing parts 12 may be molded directly on the sections A and B or may be in the form of readily re-

placeable inserts. As illustrated in Figs. 1 to 6, inclusive, of the drawings, the bearing parts are formed of two substantially semi-annular rings 34 and 35 and have alternate longitudinal depressions 31 and projections 32 on their outer faces. The projections 32 project radially outward from the outer sides of the rings 13 and 14, so that the cage and object P cannot engage the well casing or walls of the well bore W. The ribs or projections 32 have curved or rounded exteriors as illustrated throughout the drawings. The inner surfaces or sides 33 of the bearing parts may be substantially flush with the projections 17 of the rings 13 and 14 so that they seat against the object P as shown in Figs. 2 and 3. If desired, the parts 33 and 34 may be proportioned so that their inner sides 33 are spaced from the pipe P when the protector is in the pipe so that they are free to give or flex to a considerable degree.

The parts 34 and 35 may be detachably mounted on the parts A and B by means of a plurality of circumferentially spaced pins 36. The pins 36 are arranged through openings 37 in the bumpers or bearing parts 33 and 34 extending into openings or sockets 40 in the lower ring 14. The upper ends of the pins 36 extend into openings 39 in the ring 13 which may have their upper edges peened over to prevent the pins from becoming displaced. The lower portions of the openings 30 of the lower ring 14 are reduced to present shoulders to retain the pins in position. The reduced portions of the openings 40 are adapted to receive a punch or drift which may be employed to drive out the pins when it is desired to remove the parts 33 or 34 for replacement, etc. The openings 39 and 40 may be provided through the projections 17 of the rings 13 and 14, and are arranged in vertical alignment. The ribs 15 of the cage extend through spaced recesses or depressions 31 in the bearing parts. The ribs 15 aid in preventing the bearing parts from binding and from becoming displaced.

It will be apparent from the foregoing detailed description that the protector described above is particularly simple and inexpensive of construction. When the protector is assembled the semi-annular bumpers 13 are slipped into place on the sections A and B from their inner sides. The pins 36 may then be arranged in position. The sections A and B are then arranged about the pipe P and the pin 25 is inserted through the openings in the overlapping parts 19 and 20 to cause the gripping parts 30 to be forced into the pipe.

The embodiment of the invention illustrated in Figs. 7 to 9, inclusive, of the drawings embodies a plurality of circumferentially spaced replaceable bearings or wear receiving parts 60 mounted on a cage 10^a. The cage 10^a employed in this form of the invention may be of substantially the same configuration as the cage 10 of the form of the invention illustrated in Figs. 1 to 6, inclusive, of the drawings.

The cage 10^a is an integral or unitary structure adapted to be slid over an end of a pipe P, or the like. The cage 10^a is an annular structure including vertically spaced rings 13^a and 14^a connected by vertical or longitudinal ribs 15^a. The rings 13^a and 14^a are each provided with a plurality or series of circumferentially spaced enlargements 61. The enlargements 61 present spaced inwardly projecting portions or projections 62 on the inner sides of the rings and their outer sides present projections 63 on the outer

sides of the rings. In practice the cage 10^a may be proportioned so that it may be readily slid onto the pipe P. The projections 61 of the two rings 13^a and 14^a are preferably in vertical or 5 longitudinal alignment. The ribs 15^a are connected with the rings 13^a and 14^a at points spaced between the projections 61.

The bearing parts 60 are in the nature of bearing or wear receiving parts and are adapted to 10 engage the wall of a well bore or a casing C to prevent excessive wearing of the casing and the pipe P. The bearing parts 60 may be formed of rubber or a suitable rubber composition and are mounted on the cage 10^a so that they may be 15 easily and quickly replaced when worn. In accordance with this embodiment of the invention the bearing parts 60 extend between the rings 13^a and 14^a and are removably attached to the cage 10^a by pins 64. The pins 64 are arranged 20 in openings or sockets in the enlargements 61 of the rings and may be secured to the cage 10^a in the same manner as the pins 36 of the form of the invention described above. The pins 64 extend through longitudinal openings 90 in the 25 bearing parts 60. The upper ends of the bearing parts 60 engage against the lower side of the ring 13^a and the lower ends of the bearing parts engage against the upper side of the rings 14^a so that the bearing parts are held against longitudinal 30 movement on the pins 64.

The bumpers or bearing parts 60 are proportioned so that they project outwardly beyond the projections 63 of the cage 10^a. The outer projecting portions of and parts 60 are preferably 35 rounded as clearly illustrated in Figs. 7 and 9 of the drawings. The sides 66 of the parts 60 may be flat and may diverge inwardly toward the pipe P. It is preferred to mount the bearing parts 60 so that they are held against rotation on the pins 64. In the particular case illustrated the inner sides 67 of the several parts 40 60 are shaped to substantially conform to the exterior of the pipe P so that they seat against the pipe P and hold the bearing parts against 45 rotation. However, if desired or found practical, the bearing parts 60 may be proportioned so that their inner sides 67 are spaced short distances from the exterior of the pipe P. In the construction illustrated, where the bearing parts 50 60 are in engagement with the pipe P when the device is assembled on the pipe, inward thrusts on the bearing parts are transmitted to the pipe P by the bearing parts 60 so that the bearing parts and the pins 64 are not distorted or fractured. It is preferred to proportion the bearing parts 60 so that they are spaced apart around the cage 10^a as illustrated in the drawings.

Means is provided for mounting or setting the 55 cage 10^a on the pipe P so that it is positively held against movement on the pipe. A plurality of grips or gripping parts 68 are provided to prevent movement of the protector on the pipe when it is in the operating position. The grips 68 are arranged in the inner ends of lateral or radial 60 openings 69 in the rings 13^a and 14^a. The gripping parts 68 are preferably formed of hardened or tempered steel and are provided at their inner ends with sharpened points 70 to grip or bite into the pipe P. The invention provides means for forcing the points 70 of the parts 68 into the pipe P and to retain the gripping parts in their gripping position. Set screws 71 are screw threaded into the openings 69 to engage the outer sides of the gripping parts 68 to force them into effective engagement with the pipe. The screws 71 may

be employed to lock the cage 10^a on the pipe P in any suitable position and may be unthreaded from the opening 69 to release the grips 68 when it is desired to remove or shift the protector.

It will be obvious that bearing parts or wear 80 receiving parts of the same character as the parts 60 described above may be mounted on the pins 36 of the cage 10 in substitution of the bearing parts 13 and 14 without in any way altering the cage 10. Further, unitary bearing parts of the same general character as the parts 13 and 14 may be mounted on the pins 64 of the form of the invention illustrated in Figs. 7 to 9, inclusive, of the drawings, without modifying the construction. It is to be noted that both forms of the invention include replaceable resilient bearing parts or bumpers that may be easily and quickly mounted on a rigid cage.

The cages 10 and 10^a are effectively secured on the pipe so that they are positively held against circumferential and longitudinal movement. The cages are such that they may be used for long periods and may be provided with new bumpers or bearing parts whenever it becomes desirable or necessary.

Having described only typical preferred forms of our invention, we do not wish to limit ourselves to the specific details set forth, but wish to reserve to ourselves any changes or variations that may appear to those skilled in the art or fall within the scope of the following claims:

Having described our invention, we claim:

1. A bearing device for a string of drill pipe, a cage adapted to be arranged on the drill pipe, the cage including two vertically spaced rings, and a spacer rib connecting the rings, and a plurality of spaced bumpers between the rings and spaced from the rib, the outer sides of the bumpers projecting beyond the rings and the inner sides of the bumpers engaging the drill pipe.

2. A bearing device for a string of drill pipe including, a cage adapted to be arranged on the drill pipe, the cage including two vertically spaced rings, and a spacer rib connecting the rings, and a plurality of individual stationary rubber bumpers between the rings, the outer sides of the bumpers projecting beyond the rings and the inner sides of the bumpers in abutment with the drill pipe.

3. A device of the character described adapted to be mounted on a drilling string including, a cage adapted to be arranged on the string including, two spaced rings, and a plurality of ribs connecting the rings and spaced from the string, means for holding the cage against movement on the string, and a plurality of circumferentially spaced rubber bumpers mounted between the rings and spaced between the ribs.

4. A device of the character described adapted to be mounted on a drilling string including, a cage adapted to be arranged on the string, the cage including two spaced rings, ribs connecting the rings, means for holding the cage against movement on the string, said means including hard metal grips on the rings for biting into the string, and a plurality of stationary circumferentially spaced bumpers mounted between the rings spaced between the ribs and having outer curved projections, extending beyond the rings, and inner faces adjacent the string.

5. A device of the character described adapted to be mounted on a drilling string including, a cage adapted to be arranged on the string, the cage including two spaced rings, and ribs connecting the rings, means for holding the cage

against movement on the string, a pin extending between the rings, and a stationary bumper mounted on the pin.

6. A bearing device for use on a string of drill pipe including, a cage adapted to be arranged on the drill pipe, the cage including two spaced rings, and ribs connecting the rings, means for holding the cage against movement on the pipe, a removable pin extending between the rings, a bumper stationary on the pin and projecting outwardly beyond the rings, the pin having an end seated in a socket in one ring and opposite ends extending into openings through the other ring.
